United States Patent

Des. 235,866
Patented July 15, 1975

235,866

RETAINER FOR BANK CASH SLIPS OR SIMILAR ARTICLE

Robert E. Seitz, 646 17th St.,
Nevada, Iowa 50201

Filed Dec. 26, 1973, Ser. No. 428,115

Term of patent 14 years

Int. Cl. D19—02

U.S. Cl. D19—88

FIG. 1 is a perspective view of a retainer for cash bank slips showing my new design;

FIG. 2 is an enlarged scale top plan view thereof;

FIG. 3 is a left side elevational view thereof;

FIG. 4 is a rear elevational view; and

FIG. 5 is a front elevational view.

I claim:

The ornamental design for a retainer for bank cash slips or similar article, substantially as shown and described.
